GAUGE FOOT FOR SEWING MACHINES

Filed June 9, 1947

UNITED STATES PATENT OFFICE

2,478,032

GAUGE FOOT FOR SEWING MACHINES

Jacob Wallsh, Brooklyn, N. Y.

Application June 9, 1947, Serial No. 753,418

4 Claims. (Cl. 112—235)

1

This invention relates to a gauge foot for sewing machines.

It is an object of the present invention to provide a gauge foot which is adjustable and which will still be provided with a smoothing surface extending throughout the length of the gauge which is offset from the sewing machine foot and wherein the gauge foot does not have to be completely disassembled from the sewing machine foot in order to adapt the same for different widths.

It is another object of the present invention to provide an adjustable gauge foot or stitching gauge including smoothing elements of different sizes or widths which may be severally or singularly assembled upon a bar which extends from the side of the sewing machine foot and retained thereon wherein simple devices are provided for retaining the several smoothing elements upon the bar when located beside one another and interlocking means for preventing relative rotation of the elements with respect to one another and for maintaining a flush and continuous bottom or smoothing surface.

Other objects of the present invention are to provide an adjustable stitching gauge or gauge foot for sewing machines which is of simple construction, inexpensive to manufacture and efficient in operation.

For a better understanding of the invention, reference may be had to the following detailed description taken in connection with the accompanying drawing, in which

Fig. 1 is a perspective view of a sewing machine foot having means thereon for the attachment thereto and the securing thereof of my adjustable stitching gauge or gauge foot.

Fig. 2 is a collective and perspective view of my gauge foot detached from the sewing machine foot.

Fig. 3 is a transverse cross-sectional view taken across the sewing machine foot and looking in plan upon the top of my adjustable gauge foot with fragments of the gauge foot broken away to show the connection of one of the elements to the guiding plate at the end of the bar.

Fig. 4 is a perspective view of a sewing machine foot with my gauge foot secured thereto and extended to a maximum width and on which a plurality of smoothing elements have been mounted.

Fig. 5 is a fragmentary and top plan view of the end of my gauge foot on which a plurality of different size elements have been assembled and broken away to show the interconnection between the elements to retain them against movement

2

relative to one another when mounted upon the gauge bar.

Fig. 6 is a top plan view of one of the elements.

Fig. 7 is a side elevational view of a modified form of element which can be attached to the gauge bar without the removal of the bar from the sewing machine foot and wherein there is a spring clip means for retaining the element in the elevated position upon the bar.

10 Fig. 8 is a side elevational view of a modified form of gauge element and showing a different type of means for retaining the gauge element on the bar.

Referring now particularly to Figs. 1, 2 and 3, 15 Fig. 1 represents a sewing machine foot through which a needle is extended to form a stitching 16. This foot 15 has a spring member 17 adapted to retain my gauge foot device 18 within a recess 19 at the top of the foot.

20 My gauge foot device includes a bar 21 adjustable through the recess 19 and on the gauging end of the same is a guide plate 22 adapted to run along the edge of a sheet of material 23 or along another stitching from which the stitching 16 is

25 to be gauged or governed. As shown in Fig. 1 a wide smoothing element 24 is mounted on the bar 21 and retained flush against the guide plate 22. This smoothing element 24 may be of variable width and will govern the distance to which the

30 stitching 16 is to be applied to the sheet 23 from the edge thereof. This element has an opening 25 for receiving the bar 21. The element also has a projection 26 adapted to be extended into a hole 27 in guide plate 22 or in holes 28 of adjacent

35 smoothing elements assembled on the bar as shown in Figs. 4 and 5. This hole and projection arrangement will retain the smoothing elements against vertical displacement from one another and to maintain a smooth and continuous bottom

40 smoothing surface of the several smoothing elements on the bar 21.

Referring now particularly to Fig. 7, there is shown a modified form of smoothing element as indicated at 31 with a bottom smoothing surface

45 32. The smoothing element 31 has a top slot 33 adapted to receive the bar 21 when extended into the slot from the top edge of the element 31. Into the opening 33 is a retaining element 34 which is backed up by a spring strip 35 secured along with the retaining element 34 to the top of the smoothing element 31 by a screw 36.

In Fig. 8, there is a modified form of smoothing element in which the opening or slot is extended into the rear end of the element as indicated at

55 37. The rear end of the slot 37 has diverging top

and bottom faces adapted to receive a V-shaped portion 38 of a spring strip 39 secured to the top of the element by a screw 41.

It will be apparent that there has been provided a gauge foot for sewing machines which is adjustable to different widths by the utilization of different size smoothing elements and wherein the smoothing elements can be applied to the supporting bar of the foot without removing the bar from the sewing machine foot and wherein there is means provided on the several elements for retaining the same on the bar against displacement.

Having thus described my invention, I claim:

1. A gauge foot for sewing machines adapted to be attached to the sewing machine foot comprising a bar having a guiding plate on one end of the same and adapted to be adjustably clamped to the sewing machine foot to different positions, and a smoothing element of predetermined width having a recess formed therein and said bar being positioned in said recess whereby said smoothing element is releasably and slidably mounted on the bar and which when the bar is clamped to the sewing machine foot is adapted to provide a smoothing surface between the guide plate on the end of the bar and the sewing machine foot, the smoothing element being engageable with the sewing machine foot to set off the guiding plate a measured distance from the sewing machine foot, said guiding plate having a portion thereon extending below said bar, the inner surface of which is adapted to serve as an edge guide, said smoothing element having a surface extending below the said bar a lesser distance than the bottom surface of the said guiding plate and extending the full width of the element.

2. A gauge foot for sewing machines adapted to be attached to the sewing machine foot comprising a bar having a guiding plate on one end of the same and adapted to be adjustably clamped to the sewing machine foot to different positions, and smoothing elements of predetermined widths having recesses formed therein and said bar being positioned in said recesses whereby said smoothing elements are releasably and adjustably mounted on the bar and which when the bar is clamped to the sewing machine foot are adapted to provide a smoothing surface between the guide plate on the end of the bar and the sewing machine foot, the smoothing element most removed from the guide plate being engageable with the sewing machine foot whereby to set off the guiding plate a measured distance from the sewing machine foot, and means for interlocking the smoothing elements together and any one of the elements to the guide plate whereby to maintain the smoothing elements against vertical displacement relative to one another.

3. A gauge foot for sewing machines adapted to be attached to the sewing machine foot comprising a bar having a guiding plate on one end of the same and adapted to be adjustably clamped to the sewing machine foot to different positions,

and smoothing elements of predetermined width adapted to be releasably and adjustably mounted on the bar and which when the bar is clamped to the sewing machine foot are adapted to provide a smoothing surface between the guide plate on the end of the bar and the sewing machine foot, and each of said smoothing elements having a top slot therein extending downwardly from the top face of the element and adapted to receive the bar, and to permit the connection of the element to the bar without the removal of the bar from the sewing machine foot and spring strip means secured to the top of the element and extending into the opening for engagement with the bar whereby to retain the element upwardly against the bar, said smoothing elements being engageable with one another to set off a measured distance from the sewing machine element and the smoothing element most removed from the guide plate being engageable with the sewing machine foot.

4. A gauge foot for sewing machines adapted to be attached to the sewing machine foot comprising a bar having a guiding plate on one end of the same and adapted to be adjustably clamped to the sewing machine foot to different positions, and smoothing elements of predetermined width adapted to be releasably and adjustably mounted on the bar and which when the bar is clamped to the sewing machine foot are adapted to provide a smoothing surface between the guide plate on the end of the bar and the sewing machine foot, and each of said smoothing elements having a slot extending inwardly from its rear end and spaced from the upper and lower surfaces whereby to permit the smoothing element to be slid rearwardly over the forward edge of the bar and to permit the connecting of the element to the bar without the removal of the bar from the sewing machine foot, said slot having diverging faces at its open end, a spring strip having a V-shaped portion adapted to extend into the slot to about the rear edge of the bar and the diverging faces of the slot whereby to retain the elements upon the bar, said smoothing elements being engageable with one another to set off a measured distance from the sewing machine element and the smoothing element most removed from the guide plate being engageable with the sewing machine foot.
